UNITED STATES PATENT OFFICE.

WILLIAM W. EDWARDS, OF LOS ANGELES, CALIFORNIA.

RADIAL DRILL.

Application filed January 22, 1923. Serial No. 614,111.

My invention relates to a drilling machine of the type commonly known as radial drills.

An object is to provide a novel bearing construction whereby a horizontal and a vertical shaft may be supported relative to each other and gear connections between the shafts enclosed in a lubricant-containing chamber, and in which the shafts may have longitudinal movement through the bearing without discharge of lubricant from the chamber.

A further object is to provide a machine of the above character in which the parts are of simple construction and adapted to be readily assembled or dismantled, and in which the wearing parts may be readily lubricated and be easily removed and replaced in event of excessive wear.

With the foregoing objects in view together with such other objects as may subsequently appear, my invention resides in the parts and in the construction, combination and arrangement of parts hereinafter described and claimed and illustrated in the accompanying drawings, in which

Fig. 1 is a view in horizontal section of the device as seen on the line 1—1 of Fig. 2;

Figure 2 is a view in section and elevation as seen on the line 2—2 of Figure 1 on a reduced scale.

Referring to the drawings more specifically, 45 indicates a guideway on one side of which is a revoluble drive shaft 48 supported in suitable bearings.

A carriage 20 is mounted to slide longitudinally on the guideway 45 and the shaft 48, which carriage and its allied parts constitute an important feature of the machine, and will therefore be now described in detail.

The carriage embodies a back wall portion 60 mounted to slide on the guideway 45 there being a dovetail sliding engagement between the upper and lower edges of the guideway 45 and the back wall 60 of the carriage, as indicated at 61 and 62 in Figure 2. Mounted on the front of the back wall portion 60 is a housing embodying a pair of side walls 65 and 66 having inner end faces *d* and *e* which abut against the face *c* of the back wall and are secured thereto by suitable fastenings. The side wall portions 65 and 66 are connected together adjacent their lower ends by a transverse wall 70 which abuts against the wall *c* on the back wall member 60, the upper and lower edges of the wall portion 70 extending flush with the upper and lower edges of the back wall 60, as particularly

shown in Figure 2. The adjacent faces of the walls 60 and 70 are formed to receive a bearing 71 through which a vertical revoluble shaft 72 extends, as will be later described. 60 The lower portions of the side walls 65 and 66 extend adjacent the horizontal revoluble shaft 48 and are formed to receive a bearing 76 through which the shaft 48 extends, as will be later described. 65

The bearing 76 includes a pair of bushings 77 and 78 which are mounted in recesses 79 and 80 in the front end walls of the side walls 65 and 66 which bushings are held in place by a cap plate 81, particularly shown in Figure 2. Turnable in the bushings 77 and 78 is a sleeve 82 the ends of which project beyond the outer ends of the bushings and are externally threaded. The sleeve encompasses the shaft 48 and is splined on the latter by 75 means of a key 83 which slidably extends in a keyway 84 formed longitudinally of the shaft 48; the key being fastened relative to the sleeve by means of an internally threaded ring 85 which is screwed on the end of the 80 sleeve 82 and engages threads 86 on an in-turned end formed on the key 83, as shown in Figure 1. An internally threaded ring 85' is screwed on the end of the sleeve 82 and cooperates with the ring 85 in holding the 85 sleeve 82 against longitudinal movement in the bushing. By this construction, rotation of the shaft 48 will effect rotation of the sleeve 82, yet permit movement of the sleeve longitudinally of the shaft. Formed on the 90 sleeve 82 is a helical gear 87 which meshes with a worm 88 on a sleeve 89 encircling the shaft 72; the sleeve being splined on the shaft 72 by a key 90 slidably mounted in a keyway 91 formed longitudinally of the shaft 72. 95 The sleeve 89 extends through bushings 92 and 93 carried between the walls 60 and 70 and has externally threaded ends projecting beyond the ends of the bushings on which are screwed internally threaded rings 94 and 94' 100 by which the sleeve 89 is held against longitudinal movement between the walls 60 and 70. The ring 94 engages a threaded portion 95 formed in the key 90 by which the latter is fastened relative to the sleeve. By this 105 construction, rotation of the sleeve 89 by the gears 87 and 88 effects rotation of the shaft 72 and permits longitudinal movement of the shaft relative to the sleeve.

When the bushings 82 and 89 are assembled 110 as just described, with the cap 81 extending over the gear 87, the gears 87 and 88 will be

completely housed within a chamber 96, which chamber is designed to contain suitable lubricant, which, because of the sleeves extending through the bushings, will not 5 contact the shafts 48 and 72, and therefore cannot escape from the lubricant chamber 96 through the keyways 84 and 91. This constitutes the important feature of my invention.

10 While I have shown and described the specific embodiment of my invention, I do not limit myself to the exact details of construction and arrangement shown, but may employ such modifications and changes as 15 come within the scope of the appended claims.

I claim—

1. An enclosed lubricating chamber, a rotary shaft mounted for longitudinal movement through said chamber, a sleeve encircling said shaft and splined thereto arranged in said chamber and extending through the walls thereof, bushings encompassing the end portions of said sleeve carried by the chamber walls, rings on said sleeve exteriorly 25 of the chamber adjacent the outer ends of the bushings for inhibiting longitudinal movement of the sleeve relative to the chamber walls, a gear on said sleeve, a driving shaft extending through said chamber, a sleeve encircling said driving shaft and splined thereon, bushings encompassing the end portions 30 of said sleeve and extending through the walls of the chamber adjacent the outer ends of

said sleeve for inhibiting the longitudinal movement of said sleeve relative to said chamber, and a gear on said sleeve meshed with the first named gear. 35

2. An enclosed housing forming a lubricant chamber, a driven shaft extending through said chamber, a sleeve splined on said shaft and extending through the walls of 40 said chamber, a gear wheel on said sleeve, a second sleeve extending through said chamber, a gear on said second sleeve meshing with the first named gear, and a drive shaft 45 extending through said second sleeve on which said sleeve is splined, whereby on rotation of said drive shaft said sleeve may be rotated through the intermediary of said gears to effect rotation of said driven shaft. 50

3. In a machine of the class described, a power driven shaft, a sleeved gear wheel splined to said power driven shaft, a shaft disposed at right angles to said power driven shaft, a sleeved gear wheel splined to the 55 last named shaft, a chamber enclosing both of said sleeved gear wheels and provided with a pair of bearings for each sleeve of each gear wheel whereby said chamber and the sleeves of said gears provide a lubricant container and whereby said chamber may be moved with relation to both of said shafts without leakage between the chamber and shafts. 60

WILLIAM W. EDWARDS.
